UNITED STATES PATENT OFFICE.

MAXIME CHARLES BRENOT, OF ISSY-LES-MOULINEAUX, FRANCE, ASSIGNOR TO THE FIRM OF ROBERT BOSCH, OF STUTTGART, GERMANY.

MAGNETO-ELECTRIC GENERATOR.

1,084,924.

Specification of Letters Patent.

Patented Jan. 20, 1914.

Application filed March 18, 1912. Serial No. 684,478.

To all whom it may concern:

Be it known that I, MAXIME CHARLES BRENOT, a citizen of the French Republic, residing at 3 Avenue Bourgain, Issy-les-5 Moulineaux, Seine, France, have invented certain new and useful Improvements in Magneto-Electric Generators; and I do hereby declare the following to be a full, clear, and exact description of the invention, 10 such as will enable others skilled in the art to which it appertains to make and use the same.

My invention relates to magneto-electric generators such as are employed for igniting 15 the combustible mixtures in the cylinders of internal combustion engines and more especially to devices for controlling the mechanical interrupter associated with generators of this kind, where the igniting generator is 20 intended for operation with multicylinder engines having an irregular order of ignition, such as for instance multicylinder engines with the cylinders arranged in the shape of a fan.

5 In the usual form of mechanical interrupter, a disk fastened on the armature shaft carries a relatively stationary electrode and a movable electrode nominally spring pressed into engagement therewith, 30 but capable of being deflected to a position of disengagement by stationary cams, which are usually arranged in such manner as to deflect the movable electrode and thus interrupt the ignition circuit at certain points of 35 the rotation of the armature. In two-cylinder-engines this known apparatus can be arranged to act satisfactorily, though the engine, from the position given to its cylinders, may require an irregular order of ignition.

40 In that case the armature of the igniting machine is coupled to the valve controlling shaft which is driven at half the speed of the crank and, by a proper displacement of the stationary cams, the moments of interruption 45 can be correspondingly displaced to conform to the required order of ignition. But in multicylinder engines requiring an irregular order of ignition it is imperative to interpose gearing between the valve controlling 50 shaft and the armature shaft of the igniting machine and on the other hand it is important that the interrupter should be mounted on the armature shaft and rotate therewith, so as to obviate the necessity, 55 otherwise existent, of interposing sliding

contacts between the armature winding and the insulated electrode of the interrupter.

It is the object of my invention to provide means for controlling the interrupter in cases of this kind, though it is mounted on 60 and revolves with the armature shaft.

My invention consists in providing movable cams in the place of the usual stationary cams and interposing transmitting mechanism between the armature shaft and the cams by which they are operated and controlled in such a manner that they engage and operate the interrupter lever in the moments in which ignitions and therefore 65 interruptions are required.

As a rule the irregularities required by fan shaped multicylinder motors, or any other multicylinder motors requiring an irregular order of ignition, can be expressed by alternately advancing and retarding interruptions which otherwise are arranged to follow each other in a regular order. Therefore the simplest method of reducing my invention to practice would be to provide a disk concentric to the interrupter disk and 70 pivoted to be rocked on an axis coinciding with the axis of the armature shaft, said disk carrying the cams for intercepting and rocking the interrupter lever and means for rocking the said disk alternately to advance 75 and to retract the cams between consecutive revolutions of the interrupter disk or otherwise in proper time to produce the desired order of ignition. Another manner and the one I prefer, consists in mounting the cams 80 on parts of mechanism operated by the armature shaft and adapted to advance them radially or axially into the path of the interrupter lever in the moments in which interruptions are required.

95 In the drawing Figure 1 is a diagrammatical perspective view of mechanism to be mounted on the frame of an igniting generator and to be operated by its shaft to advance and retract interrupter cams and Fig. 2 is a diagrammatical end view of the same mechanism. Fig. 3 is a front elevation partly in section of a magneto-electric generator provided with mechanism embodying my present invention and Fig. 4 is a horizontal longitudinal section on line 4—4 of Fig. 3. Fig. 5 is a diagrammatical front elevation of a form of the mechanism embodying my invention adapted to a six-cylinder engine and Fig. 6 a diagram illustrating the 100 105 110

order of ignition produced thereby. Fig. 7 is a diagram illustrating a modification of the mechanism producing irregular ignition suitable for a four-cylinder engine and Fig. 8 a development of the same diagram on a straight line. Fig. 9 is a front elevation partly in section of a magneto-electric machine provided with the arrangement indicated by Figs. 7 and 8 and Fig. 10 a horizontal longitudinal section on line 10—10 of Fig. 9.

The same reference numerals represent corresponding parts in all the figures.

Referring to Figs. 1 to 4, 20 represents the armature shaft of a magneto and 21 a pinion keyed to the said shaft. The other shafts 22 and 23 are journaled in the frame of the magneto on each side of the armature shaft and on them are mounted two pinions 24 and 25 meshing with pinion 21. In the present instance these pinions 24 and 25 are dimensioned to make the shafts 22 and 23 rotate at half the speed of the armature shaft when the latter is driven. On the outer ends 25 of shafts 22 and 23 cams 26 and 27 are mounted to revolve with the shafts. On the interrupter disk 28 is mounted an insulated electrode 29 and a lever 30 carrying the earthed electrode 31 of the interrupter. The outer arm of the interrupter lever 30 carries a button 32 and as the cam shafts 22 and 23 revolve the cams 26 and 27 alternately are projected into the path of the button 32 and retracted therefrom. In the present instance stationary cams 33 and 34 are also provided mounted on a stationary ring or disk in the usual manner and placed to constantly intercept the path of the button 32 on the outer arm of interrupter lever 30.

In Fig. 2 the electrical connections of the arrangement are shown. The armature has two windings a primary 35 and a secondary 36. One terminal of both windings is earthed and the other terminal of the secondary winding is connected to the spark plugs 37. The insulated terminal of the primary winding is connected to the insulated electrode 29 of the interrupter.

The action of this arrangement is as follows: Figs. 1 and 2 show the position of the mechanism in the moment of ignition of the first cylinder. The cam 26 is projected into the path of button 32 and effects an interruption and consequently an ignition spark at the spark plug 37. The button 32 then passes over the stationary cam 33 without effect because the cam 33 is so near cam 26 that the electrodes 29, 31 have not had time to close. When the button 32 then moves one half revolution where it strikes cam 27, which in the meantime has been turned around so as to be projected into its path by means of the gearing 21, 24, 25, a second interruption causing the ignition of the second

cylinder follows and the button again passes over the stationary cam 34 without effect. The button proceeds until it stands opposite cam 26. This cam in the meantime has been turned so as to be out of the way of the button and the latter therefore strikes the stationary cam 33 and is deflected so as to break contacts and cause the ignition of the third cylinder. But the interval between the two latter ignitions is not 180° but rather $180^\circ - d^\circ$, if the angle separating the stationary cam 33 from the movable cam 26 is d° . When the button passes under cam 27 this cam has again been averted, so that the button strikes the stationary cam 34 after another half revolution causing the ignition of the fourth cylinder and then the same play is repeated and so forth. Thus the order of ignitions obtained is:

$180^\circ; (180+d)^\circ; 180^\circ; (180-d)^\circ$.

Figs. 5 and 6 illustrate an adaptation of the invention to a six cylinder engine requiring an order of ignition as follows:

$120^\circ; 120^\circ; 140^\circ; 120^\circ; 120^\circ; 100^\circ \dots 120^\circ$

and so forth, measured on the crank shaft. The pinion 21 mounted on the armature shaft is driven by a pair of gear wheels 38, 38¹ of which the former is mounted on or revolves in synchronism with the crank shaft and which are so dimensioned that the armature revolves three times for every two revolutions of the crank shaft. The diameter drawn through the two stationary cams 33 and 34 embraces an angle of 30° with the diameter drawn through the axes of the two movable cams 26 and 27. The pinions 24 and 25 are dimensioned to perform one revolution for every three of the pinion 21. The cam 26 in this instance has two projections 26' and 26'' removed 120° from each other. In the position of the parts shown in the drawing, button 32 is in the act of striking the projection 26' on cam 26 and cam 27 is removed 60° from its operative position. This is, as in the above described instance, the position in which cylinder I is ignited. Button 32 revolves 180° and cam 27 simultaneously revolves 60° . Therefore the button strikes the cam and ignites cylinder II. Button 32 again revolves 180° making 360° from the start and simultaneously cam 26 has revolved 120° . Therefore projection 26 is presented and cylinder III is ignited. Button 32 after a further half revolution finds projection 27 averted and after

$180^\circ + 30^\circ = 210^\circ$

strikes the stationary cam 34 igniting cylinder IV. Button 32 then finds both projections 26' and 26'' averted and strikes stationary cam 33 after proceeding 180° and ignites cylinder V. In passing cam 27 the button has performed $\frac{2}{3}$ revolutions and

therefore cam 27 is still 180° removed from its operative position and the button strikes stationary cam 34 after revolving 180° igniting cylinder VI. Upon completing the 5 third revolution the button finds cam 26' returned to its initial position, and ignites cylinder I, making the last interval

$$180^\circ - 30^\circ = 150^\circ$$

10 and so forth. The order of ignition thus obtained is represented by the diagram Fig. 6 and is composed of the following intervals:

$$180^\circ; 180^\circ; 210^\circ; 180^\circ; 150^\circ; 180^\circ; 180^\circ$$

15 and so forth measured on the circumference of the armature and since the gears 38, 38' drive the armature at a speed which is 3:2 of the speed of the crank shaft, the intervals 20 enumerated above, as required for the crank shaft, are obtained, that is to say

$$120^\circ; 120^\circ; 140^\circ; 120^\circ; 120^\circ; 100^\circ$$

25 and so forth.

Instead of providing stationary cams 33, 34 besides the movable cams 26 and 27 the same result can obviously be produced by furnishing the interrupter lever 30 with two 30 buttons removed from each other by an angle representing the excess of the longer intervals over 180° or of 180° over the shorter intervals. This modification is illustrated diagrammatically by Figs. 7 and 8 35 and an adequate constructional embodiment is shown in Figs. 9 and 10. In these latter figures all parts are identical with those already described with reference to Figs. 3 and 4, with this exception that the stationary cams 33 and 34 are omitted and instead of the button 32 on the outer arm of lever 30 two buttons 32' and 32'' are provided.

In Fig. 10 it is seen that the two buttons 32' and 32'' are also removed axially from 45 each other and the cams 26 and 27 are provided with actuating surfaces on opposite sides for either button. Thus, accordingly as the revolution of the cams is timed with relation to that of the armature shaft or the 50 interrupter disk mounted thereon, either button 32' or button 32'' will be deflected and the consecutive ignition will be advanced or retarded to produce the required irregular order of ignition.

55 Instead of advancing the cams in a radial direction to intercept the path of the button, they might be arranged to be advanced axially, or if the interrupter lever 30 were pivoted to be rocked in an axial direction they might be moved either axially or radially to alternately intercept the path of button 32 or allow it to pass.

I desire it to be understood that these and other modifications of the mechanisms individually described might be worked out by

substituting equivalents to the preferred elements of construction without affecting the nature of my invention.

Having thus described my invention, what I claim is:

1. The combination with an ignition current generator driven from a multicylinder explosion engine which requires an irregular order of ignition, of interrupter mechanism comprising interrupter contacts electrically 70 connected to the generator, and a plurality of cams arranged to move the interrupter contacts relatively to each other at the irregular intervals of ignition required by the engine.

2. The combination with an ignition current generator driven from a multicylinder explosion engine which requires an irregular order of ignition, of interrupter mechanism comprising rotatable interrupter contacts 75 driven from the engine and electrically connected to the generator, and a plurality of rotatable cams driven from the engine at an angular speed different from that of the interrupter contacts, the arrangement being 80 such that the interrupter contacts are moved relatively to each other by the cams at the irregular intervals of ignition required by the engine.

3. In magneto-electric generators for 95 igniting multicylinder explosion engines requiring an irregular order of ignition the combination with an armature shaft, an interrupter arm mounted thereon and revolving therewith, of cams adapted to deflect 100 said arm to interrupt the armature current and thereby to cause ignition, said cams being eccentrically mounted on revoluble shafts, and of means for revolving said cam shafts in time with the revolution of the 105 armature shafts.

4. In magneto-electric generators for 110 igniting multicylinder explosion engines requiring an irregular order of ignition, the combination with an armature shaft and an interrupter lever mounted thereon and revolving therewith, of cams adapted to rock 115 said lever to interrupt the armature current and thereby to cause ignition, said cams being eccentrically mounted on shafts journaled parallel with the armature shaft and coupled thereto by means of transmitting mechanism adapted to time the revolution of the cam shafts to correspond to the required order of ignition.

5. In magneto-electric generators for 120 igniting multicylinder explosion engines requiring an irregular order of ignition, the combination with an armature shaft and an interrupter lever mounted thereon and revolving therewith, of cams adapted to deflect 125 said lever to interrupt the armature current and thereby cause ignition, said cams being eccentrically mounted on shafts parallel with the armature shaft, of gearing interposed be-

tween the armature shaft and the cam shafts, and of additional stationary cams in the path of the interrupter lever.

6. In magneto - electric generators for igniting multicylinder explosion engines requiring an irregular order of ignition, the combination with an armature shaft and an interrupter lever mounted thereon and revolving therewith of cams adapted to rock said lever to interrupt the armature current and thereby cause ignition, said cams being eccentrically mounted on shafts journaled in the magneto casing parallel with the armature shaft and coupled to said shaft by means of gear wheels and one of said cams having a plurality of projections disposed on its circumference to intercept the path of the interrupter lever several times during the revolution of the cam shaft.
7. In magneto electric generators for igniting multicylinder explosion engines requiring an irregular order of ignition, the combination with an armature shaft and an interrupter lever mounted thereon and revolving therewith, the operating arm of said lever being provided with a plurality of but-

tons, of cams mounted to be advanced into the paths of said buttons to deflect said lever, and of means for thus advancing the said cams according to the required order of ignition.

8. In magneto electric generators for igniting multicylinder explosion engines requiring an irregular order of ignition, the combination with an armature shaft and interrupting means mounted thereon and revolving therewith, said interrupting means being provided with a plurality of buttons placed in different planes, of a plurality of cams disposed in corresponding planes and adapted to be advanced into the paths of said buttons to actuate said interrupting means, and of means for advancing said cams according to the required order of ignition.

In testimony whereof I affixed my signature, in presence of witnesses.

MAXIME CHARLES BRENOT.
